UNITED STATES PATENT OFFICE.

CHARLES MESSICK, OF BRENTWOOD, NEW YORK.

DIAPHRAGM AND METHOD FOR MAKING SAME.

Application filed October 1, 1919. Serial No. 327,799. Renewed August 5, 1925.

My invention relates to diaphragms of the general type described in my application Serial No. 212,568, filed Jan. 19, 1918, Patent No. 1,503,696, dated Aug. 5, 1924.

5 The broad object of my invention is to provide a stationary peripheral anchorage means with an improved vibratory diaphragm under one or more kinds of tension anchored at the means.

10 Among the specific objects are the following:—

I. To incorporate within the diaphragm structure a number of separate stressed members, at least one of said members being 15 under strain of compression and others of said members being under strain of tension.

II. To incorporate within the diaphragm structure a number of longitudinal strain members radiating from a driven or driving 20 means, said members being covered with an imperforate means.

III. To incorporate within the diaphragm structure a skeleton framework arranged to sustain as far as practicable various mechanical strains, and a web separate from 25 said framework and so mounted thereupon as to expose to the air an imperforate surface of large area.

IV. To incorporate within the diaphragm 30 structure a skeleton framework having a stiff central portion and a flexible peripheral portion, said framework as a whole carrying a single web only, in order to render the diaphragm light.

35 V. To incorporate within the diaphragm structure a number of threads crossing each other at a common center, each thread being under tension and so connected that the several threads are formed into a cone, the apex 40 of which is the crossing point of the threads.

VI. To provide a tensioned vibratory diaphragm anchored at its edge to a stationary anchorage ring or frame and subjected to tension including both radial and chordal 45 components; the radial components being like those in tensioned spokes in a wheel and the chordal components being like those in a drum head made of stretched woven fabric or conventional drum-head material, in 50 which the radial tension at the center is so small as to be inadequate and even negligible for effectively communicating motion to or receiving motion from the center of a transmitter or receiver diaphragm.

Other objects will appear from the following description of the preferred construction and be pointed out in the claims. 55

Some of the improvements in the diaphragm and in the method of making it consist of building the diaphragm of stretched radial threads crossing one another in pairs at the center; connecting the radial threads by a stretched membrane; providing a central strut to separate the radial threads into upper and lower groups; and tying and 60 stitching the radial threads and the membrane together, part way between the center and the periphery, so that the central portion is formed into a stretched cone with the 65 strut under compression, while the portion 70 external to the stitching is flat. Other improvements will appear in the following description and claims.

Referring to the accompanying drawings 75 the figures, which are somewhat diagrammatic, indicate progressive steps in the method of construction of my diaphragm, except that in Figs. 1 to 8, inclusive, the membrane fabric, which is pasted on the bottom of the hook ring in the first operation, is omitted to show the other parts and the methods of 80 their assembly more clearly. This membrane fabric is shown for the first time in Fig. 9.

Fig. 1 is a plan view of a hook ring provided with pins and wound loosely with a radial thread provided with a loose draw 85 thread;

Fig. 2 is a section taken on the line 2—2 of Fig. 1, but with the loose threads omitted. 90

Fig. 3 is a plan view and shows the hook ring as in Fig. 1, but with the radial thread tightened and fastened by the draw thread to the lower end of the strut;

Fig. 4 is a section taken on the line 4—4 of Fig. 3;

Figs. 5 and 6 correspond to Figs. 3 and 4, respectively, but the threads are depressed and held to a board by thumb tacks, and additional loose radial and draw threads are 100 shown;

In Figs. 7 and 8, which correspond to Figs. 5 and 6, respectively, the thumb tacks have been removed and the loose radial thread of Figs. 5 and 6 is shown tightened and fastened by the draw thread to the top 105 of the strut;

Figs. 9 and 10 correspond to Figs. 7 and

8, but also indicate the membrane fabric pasted on the top of the hook ring, the ties connecting the upper and lower radial threads together to form a centrally disposed cone, and the stitching connecting the membrane fabric to the radial threads;

Fig. 11 is an enlarged fragmentary view showing the relative positions of the radial and draw threads at the strut, as seen in a 10 smaller scale in Fig. 7;

Fig. 12 is an enlarged fragmentary plan view including the assembly of Fig. 9 which is inverted in this figure, the structure being provided with an elastic reinforcement washer 15 and stretched upon a stretching frame;

Fig. 13 is a section on line 13—13 of Fig. 12.

The numeral 100 indicates a hook ring 20 which resembles the hook rings of banjos, and is provided with pins 101, 102, 103, 104, 105, 106, 107 and 108, to hold radial threads.

A radial silk thread 109 is provided with a loop 110 which encircles the pin 103. This 25 thread 109 extends loosely according to Fig. I, up and around pin 108, across the central portion of the hook ring 100, around pin 105 and pin 104; across the central portion of the hook ring 100, around pin 101, and to the 30 left around the pin 106; across the central portion of hook ring 100, and around the pin 103, and around the pin 102; across the central portion of the hook ring 100, around the pin 107; then down and terminates in a 35 loop III, which encircles the pin 104.

It will be noted that the portions of this radial thread 109 external to the hook ring 100 are symmetrical with respect to the internal portions, in that when the thread is 40 tightened, as will be subsequently described, the tension of the several portions of the thread 109 within the hook ring are substantially equal. It will also be noted that the portions of the radial thread 109 crossing 45 the hook ring 100 are formed in parallel pairs which facilitates their attachment to the strut 114, to be further described.

Referring to Fig. 1, a silk draw thread 112 having ends 1120 and 113 is introduced 50 alternately above and below each pair of parallel portions of the radial thread 109. Commencing at the end numbered 1120, thread 112 extends beneath thread 109 near pins 104 and 105, above near pins 106 and 55 107, beneath near pins 108 and 101, above near pins 102 and 103 and ends at 113. The end 113 of the draw thread 112 is then tightened, tied to its first mentioned end 1120 and draws the radial thread 109 into 60 its partially tensioned radial position as indicated in Fig. 3, and encircling the lower reduced diameter end portion 115 of the strut 114, as particularly shown in Fig. 4. The two portions of the radial thread 109 65 composing each pair, extend one on each

side of the strut 114 at the same level, thus securing a symmetrical attachment and compression upon the strut.

Referring to Figs. 5 and 6, in which the position of the hook ring 100 corresponds respectively to its position in Figs. 3 and 4, the radial thread 109 is indicated as held down by thumb tacks 117 onto a board, 118, so that an additional silk radial thread 120, and a silk draw thread 123, may be applied. The additional radial thread 120 is provided with terminal loops 119 and 121, and is placed in position in exactly the same manner as radial thread 109 of Fig. 1. It encircles the same pins and its draw thread 122, having ends respectively numbered 1220 and 1223, is tied in the same manner as draw threads 112, excepting that it is tied around the upper reduced diameter end portion 116 of strut 114, as indicated particularly in 85 Figs. 7 and 8.

A silk membrane fabric 124, first shown in Figs. 9 and 10 with pins 101 to 108 projecting through it, was pasted upon the hook ring 100 before any of the threads previously described were applied, and this membrane fabric has for its function the closing of the spaces between the radial threads of the diaphragm and also providing chordal tension for the vibratory portion of the diaphragm.

In Figs. 9 and 10 the silk tie threads 125, holding together the parallel radial portions of radial threads 109 and 120 are indicated, and silk stitches 126 attaching the membrane fabric 124 to the radial threads 109 and 120 are also shown. These tie threads and stitches form the radial threads into the central double cone of the diaphragm, which is of great stiffness as compared to the external flat portion of the diaphragm. Vibrations move the entire conical portion as a unit with a piston action, while the distortion caused by each vibration occurs in the flat 105 peripheral portion.

Referring to Fig. 11, which is an enlargement of the central portion of Fig. 7, the relative positions of the radial thread 120, the draw thread 122, the strut 114, and its upper end portion 116 are shown and the 115 ends of the knot of draw thread 112 are also indicated.

Referring to Figs. 12 and 13, the assembly of Figs. 9 and 10 is inverted and provided with an elastic reinforcing washer 127, fitted upon the pins 101 to 108 to reinforce the peripheral portion of the diaphragm which is then stretched upon the cylindrical portion 128 of the stretching frame 129. Hook bolts 130, provided with adjustable lock nut 125 stops 131, and thumb nuts 132 are used to draw the hook ring 100 down and stretch the diaphragm evenly upon the stretching frame 129.

The diaphragm is then coated with a res. 130

onant varnish or adhesive coating to make it air tight and to secure the radial threads throughout their entire lengths to the membrane fabric.

5. While the hook ring has been indicated with only eight pins, in practice any number of pins, preferably a large number, may be used.

Modifications of the diaphragm and the methods for making same in accordance with the progress of the art may be made and one or more of the novel elements may be used singly or in combination without departing from the spirit of the invention.

15. I claim—

1. A diaphragm provided with a stationary peripheral anchorage means and a vibratory portion including a skeleton framework having an attachment portion and several tensioned radial elements extending therefrom to the means, and imperforate means united to the framework throughout the portion of its area adjacent the framework.

25. 2. A diaphragm provided with a stationary peripheral anchorage means and a vibratory portion including a skeleton framework having an attachment portion and several tensioned radial elements extending therefrom to the means, and tensioned imperforate means united to the framework throughout the portion of its area adjacent the framework.

35. 3. A diaphragm comprising a stationary frame, a vibratory skeleton framework within the frame consisting of a central compression member, radial tensioned members extending from both top and bottom of the compression member, held together intermediately the central compression member and the stationary frame, thence extending in a common plane to the stationary frame, and imperforate means united to the vibratory framework throughout the portion of 45 its area adjacent the framework.

4. In a diaphragm structure, the combination of a plurality of long threads radiating from a common centre, each under tension, and a flexible web mounted upon said 50 threads and united thereto where adjacent to the threads.

55. 5. A diaphragm provided with a flat peripheral portion and a central double conical portion having a member under compression included between radially tensioned members.

60. 6. A diaphragm comprising a number of separate tensioned members crossing each other at a common centre and under strain; said tension members being so connected that they assume the form of a double cone.

65. 7. A stretching frame, a framework, including several radial members stretched on the frame and a member imperforate to air connected to the framework throughout the

adjacent portions of the member and framework whereby the member and framework may vibrate in synchronism.

8. A diaphragm including a number of separate radially tensioned members crossing each other at a common center and under strain, some of said members being compressed between other of said members. 70

9. A diaphragm including a number of separate radially tensioned members crossing each other at a common center and under strain, some of said members being compressed between other of said members and a strut to space half of said members away from the other half of said members. 75

10. The combination of a stationary anchorage frame provided with a vibratory diaphragm anchored at the frame and tensioned both radially and chordally. 80

11. A diaphragm structure including a stationary peripheral stretching frame, a vibratory portion mounted therein and having a center, said vibratory portion being tensioned at the frame along many radii, having substantially the same cross-sectional area under radial tension at all imaginary concentric sections thereof said vibratory portion also including means tensioned at the frame and providing chordal tension throughout substantially the whole area of 95 the diaphragm.

12. A diaphragm including a rigid peripheral stretching frame, a vibratory portion within the frame provided with a large number of radially tensioned members of 100 substantially the same cross-sectional area throughout their lengths crossing each other at the center of the vibratory portion, extending therefrom to the frame like the spokes of a wheel, whereby all parts of the 105 diaphragm may be vibrated by or vibrate the center, and also means to provide chordal tension in the vibratory portion.

13. The combination of an anchorage frame, tensioned vibratory members crossing 110 one above another therein near the centre of the frame and carrying a member imperforate to air, and means to hold said vibratory members together so as to cause the portions thereof external to the centre to lie all in 115 substantially the same plane.

14. A diaphragm provided with a stationary anchorage frame, a vibratory portion within the frame, radially tensioned members crossing each other at the centre of the frame embracing a centre member near the crossing and chordally tensioned means 120 united to the radially tensioned members where adjacent thereto.

15. The combination of a rigid anchorage frame, a vibratory diaphragm therein provided with an attachment portion, the material of the diaphragm being concentrated at said portion and radiating to the frame under radial tension, said material also being 125 130

under chordal tension to the frame external to said portion.

16. A rigid anchorage frame, a multiplicity of spaced, tensioned vibratory filaments anchored thereon, means connected to the filaments whereby the filaments may drive or be driven and means imperforate to air connected to the filaments where adjacent thereto and spanning the spaces between adjacent filaments.

17. The combination of a stationary anchorage frame provided with vibratory diaphragm anchored at the frame, tensioned both radially and chordally, said diaphragm including numerous radially tensioned filaments and numerous chordally tensioned filaments.

18. A diaphragm provided with a stationary peripheral anchorage means, a vibratory portion supported thereby and including a skeleton framework, driving means secured at the framework whereby the vibratory portion may drive or be driven, said frame-

work including tensioned members extending from said driving means to said anchorage means and imperforate means so carried by the members as to vibrate in synchronism therewith.

19. A stationary peripheral anchorage frame, a vibratory framework, the outer edge whereof is substantially flat, within the frame and including a large number of separate tensioned members anchored at the frame and imperforate means mounted upon the framework, intermediately connected thereto, and designed to vibrate in synchronism therewith.

20. A rigid stationary anchorage frame, a multiplicity of spaced, tensioned vibratory members anchored thereon, means connected to the members whereby the members may drive or be driven and means imperforate to air connected to the members where adjacent thereto and spanning the spaces between adjacent members.

CHARLES MESSICK.
